UNITED STATES PATENT OFFICE.

GILBERT McDONALD, OF AUGUSTA, KANSAS, ASSIGNOR TO HARTFORD M. MEREDITH, OF SILVER CITY, AND JAMES A. LUCAS, OF GEORGETOWN, TERRITORY OF NEW MEXICO.

METAL-PUNCH.

SPECIFICATION forming part of Letters Patent No. 310,142, dated December 30, 1884.

Application filed May 20, 1884. (No model.)

To all whom it may concern:

Be it known that I, GILBERT McDONALD, of Augusta, in the county of Butler and State of Kansas, have invented a new and Improved 5 Metal-Punch, of which the following is a full, clear, and exact description.

This invention relates to an improvement upon my compound metal-working machine shown and described in Letters Patent No. 10 288,827, which were granted to me November 20, 1883; and the present invention consists of the employment of a segmental ratchet arranged to be operated by a pawl and lever for forcing downward the cutting or punching 15 tool.

Reference is to be had to the accompanying drawing, forming part of this specification, in which the figure is a side elevation of my new and improved metal-working tool.

20 A represents the standard, formed with the base *a*, in or upon which the die-block *b* is held. The thrust-bar *c*, in which the tool *d* is held moves in a way formed by the cap-plate *e*, secured to the side of the stand- 25 ard *A*, so as to hold the thrust-bar *c* im- mediately over the die-block *b*. The upper end of the thrust-bar *c* is connected by the link *f* to the stud *g*, formed upon the shank *h* of the segmental ratchet *B*, which is pivoted 30 to the standard *A* upon the pivot *i*, which stands slightly out of center with the stud *g*, so that when the segmental ratchet *B* is rocked 35 upon its pivot *i* the stud *g* will have an eccentric action for raising and lowering the thrust-bar *c*, in substantially the same manner as de- 40 scribed in the patent above referred to. Just above the curved toothed portion *h'* of the seg- mental ratchet *B* is pivoted upon the stud *j* the hand-lever *C*, and to the lever is pivoted upon 45 the stud *k* the pawl *l*, arranged to engage with the teeth of the segmental ratchet *B*, so that by reciprocating the hand-lever *C* the pawl *l* will work forward the segmental ratchet *B* with great force, and cause the stud *g* and link *f* to force the thrust-bar *c* and tool *d* down-

ward with great force, causing the tool *d* to cut or punch the work placed upon the die-block *b*. The pawl *l* is held in contact with the teeth of the segmental ratchet *B* by the action of the spring *m*, attached to the hand-lever and arranged to press against the notch *n*, made in the upper side of the pawl. *o* is a stop-pawl for holding the segmental ratchet *B* from backward movement. This pawl *o* is pivoted upon the stud *P*, formed upon the ex- 50 tension *A'* of the standard *A*, and is held in contact with the teeth of the ratchet *B* by the spring *q*, attached to the standard *A* and ar- ranged to act against the notch *r*, made in the heel of the pawl *o*, as shown clearly in the 60 drawing.

Constructed in the manner described, with a small outlay of power at the hand-lever *C*, the segmental ratchet *B* will be forced forward with a slow movement and the thrust-bar *c* down- 65 ward with a force sufficient to cut or punch bars or plates of iron or steel.

Instead of using the pawl-lever *C* for oper- 70 ating the segmental ratchet *B*, the teeth of the ratchet might be made like cogs, and a pin- 75 ion and crank-wheel employed for operating it, and not depart from the spirit of my inven- 80 tion.

Having thus fully described my invention, I claim as new and desire to secure by Letters 75 Patent—

1. In a metal-punch, the segmental ratchet *B*, connected to the thrust-bar *c* and com- 85 bined with a pawl-lever or similar means for operating it, substantially as set forth.

2. The pivoted segmental ratchet *B*, con- 80 nected to the thrust-bar *c* by the pin or stud *g* and link *f*, in combination with the lever *C*, pawl *l*, and stop-pawl *o*, arranged to operate substantially as and for the purposes set forth. 85

GILBERT McDONALD.
